UNITED STATES PATENT OFFICE.

PETER BLONDELL, OF TONAWANDA, NEW YORK, ASSIGNOR TO THE BLONDELL STEEL COMPANY, OF BUFFALO, NEW YORK, A CORPORATION OF ARIZONA TERRITORY.

WHIFFLETREE.

No. 824,060.

Specification of Letters Patent.

Patented June 19, 1906.

Application filed October 29, 1904. Serial No. 230,592.

To all whom it may concern:

Be it known that I, PETER BLONDELL, a citizen of the United States, residing at Tonawanda, in the county of Erie and State of New York, have invented certain new and useful Improvements in Whiffletrees, of which the following is a specification.

My invention relates to improvements in whiffletrees; and its primary object is to provide a device of this character which is made of metal and which can be conveniently rolled into proper form in a metal-rolling machine and have formed integrally therewith end extensions which serve to lock the trace-couplings against accidental disconnection.

Other objects are to provide a metal bar tapering from the center thereof toward both ends and having lateral flanges gradually reduced in thickness from the center toward each end, which flanges are connected by a web of equal width throughout its length to provide opposite grooves, to provide hooks whose free end coöperate with the end extensions of the device to prevent the trace-couplings from becoming accidentally disconnected, and to so shape the hooks that they must be swung to such positions with reference to the end extensions that the trace-couplings may be detached.

The invention consists in the formation, construction, arrangement, and combination of parts to be hereinafter described, and particularly pointed out in the appended claims.

In the drawings, Figure 1 is a plan view of a complete whiffletree embodying my invention. Fig. 2 is an enlarged plan view of one end thereof, the coupling-hook being in position to allow the trace-coupling to be moved toward the free end of the same. Fig. 3 is a view similar to Fig. 2, with the free end of the hook bearing against the end extension to completely lock the trace-coupling. Fig. 4 is a transverse section on line *y* *y*, Fig. 2. Fig. 5 is an enlarged transverse section taken on line *z* *z*, Fig. 1. Fig. 6 is a perspective view of one end of the device with the coupling-hook and clip omitted. Fig. 7 is a detached perspective view of one of the coupling-hooks.

Referring now to the drawings in detail, similar numerals of reference refer to similar parts in the several figures.

The numeral 10 designates the whiffletree bar or body, which is constructed of metal.

This bar is widest at the center and tapers toward both ends, it consisting of opposite flanges 11, connected by a web 12 to form an I-bar. The grooves on opposite sides of the bar are of equal width throughout their length, and the tapering of the bar toward opposite ends is caused by the gradual reduction in the thickness of the flanges, which provides for strength where most needed and makes a neat and light device. By gradually reducing the thickness of the flanges a tapered body is obtained without tapering the web against which the strain of traction is exerted, while the central portion of the body, through which the pivot-pin passes, is greatly strengthened by the increased thickness of the flanges, thus providing a whiffletree of great strength at a considerable reduction in cost, due to the saving of material in the manufacture of the device. One of the flanges of the bar (the flange at the front of the bar when in use) is extended at each end to form end lock extensions 13, and to strengthen these extensions the web 12 of the bar is continued at opposite ends in a narrow tapering portion 14 to the extremities of said extensions. Mid-length the web 12 is provided with a bolt-hole 15, whereby the device may be attached to a vehicle, as is customary.

To each end of the bar or body I secure a clip 16 by means of rivets 17, passing through apertures 18 in the clip and apertures 19 in the ends of the body. Said clips are each formed of a strap of metal bent to fit the I-bar, as shown in Fig. 4, and having the ends thereof terminating in forwardly-projecting ears 20. Secured to each clip between the ears thereof is a coupling-hook 21, having an eye 22, which is held between the ears 20 of the clip by a pivot-bolt 23, passing through said eye and registering bolt-holes 24 in the ears, which gives the coupling-hooks the necessary pivotal movement. From the eyes 22 each hook is directed forward, as at 25, thence curved upon itself to form the bight 26 of the hook, thence curved slightly outward, as at 27, to form a space between the same and the lock extensions of the bar, and finally curving inward in rear of said extensions, as at 28, and terminating in a forwardly and inwardly directed toe 29, adapted to come in contact with the lock extensions of the bar when the hook oscillates on its

pivot, which it does in the sudden starting or stopping of the vehicle or under irregular strain, thus preventing accidental disconnection of the traces 30 from the hooks.

5 When disconnecting the traces, the movement of the same toward the free ends of the hooks tends to swing the latter against the ends of the body portion, as shown in Fig. 2, and particularly so when the trace fits snugly 10 on the hooks. This provides the necessary space to clear the lock extensions, so as to permit the trace to be brought against the toe 29, after which a slight forward pull of the hooks will throw the free end of the latter 15 away from the bar sufficiently to allow the removal of the trace from the hook.

Although I have shown my invention constructed of a bar whose cross-section is that of an I-beam, I desire my patent to cover 20 bars of different cross-sections so long as they come within the terms of the claims, which are not intended as limiting my invention to a bar whose cross-section is that of an I-beam unless specifically so stated therein.

25 Having thus described my invention, what I claim is—

1. A whiffletree formed of metal and consisting of a bar having longitudinal flanges connected by a web of equal width throughout its length, one of said flanges being gradually reduced in thickness toward opposite ends.

30 2. A whiffletree formed of metal and consisting of a bar having tapering longitudinal

flanges connected by an intermediate web of equal width throughout its length.

3. A whiffletree formed of metal and comprising a bar tapering toward opposite ends and whose cross-section is in the form of an I-beam, the longitudinal flanges of the bar 40 being gradually reduced toward opposite ends.

4. A whiffletree formed of metal and consisting of longitudinal flanges and a web connecting said flanges, one of said flanges being 45 longer than the other to form end extensions for coöperation with suitable coupling-hooks.

5. A whiffletree whose cross-section is that of an I-beam, and a clip at each end of the bar fitting around the flanges of the same 50 and having a pair of forwardly-extending ears for the reception of suitable coupling-hooks.

6. A whiffletree consisting of a bar having opposite longitudinal flanges and a web connecting said flanges, one of said flanges being longer than the other to form end extensions and the web having tapering continuations at opposite ends to strengthen said end extensions.

6c In testimony whereof I have affixed my signature in the presence of two subscribing witnesses.

PETER BLONDELL.
